UNITED STATES PATENT OFFICE.

EUGÈNE DUCHAMP, OF ST. MARTINSVILLE, LOUISIANA.

IMPROVEMENT IN FURNACES FOR EVAPORATING SUGAR-JUICES.

Specification forming part of Letters Patent No. 26,974, dated January 31, 1860.

To all whom it may concern.

Be it known that I, EUGÈNE DUCHAMP, of St. Martinsville, in the parish of St. Martins and State of Louisiana, have invented a new and Improved Sugar-Furnace; and I do hereby declare that the following is a full, clear, and exact description thereof, reference being had to the accompanying drawings, forming a part of this specification, in which—

Figure 1 represents a plan view of the furnace and boilers arranged after the manner of my invention. Fig. 2 is a longitudinal vertical section taken through the red line *xx* of Fig. 1. Fig. 3 is a transverse vertical section taken through Fig. 1, as indicated by the red line *yy*.

My invention and improvement in sugar-furnaces consists in a peculiar arrangement of the flues, fire-places, and pans, in combination with suitable steam-boilers, or boiler and pipes leading therefrom, whereby the waste heat from the battery-pan may be made to generate steam in the steam-boilers after the water in said boilers has been brought to the boiling-point, as hereinafter described and represented.

A A A are the outer walls of my sugar-works, and B B are walls upon which the steam-boilers rest, and C C are walls in the rear end of the furnace, which, with the end walls, A A, form a flue-space into the steam-boiler furnace D, between the two interior walls, B B. On top of the walls B rest the steam-boilers E E, for generating the steam to be used about the works for the cane-mill, &c. These boilers are furnished with a steam-chest, E', safety-valves, &c., and all the appendages necessary for the ordinary steam-boilers. Below these boilers is the furnace D, grate-bars *a*, and ash-pit *b*.

G G G are pipes which surround the outer walls, and which are supported upon brackets on the inside of these walls. These pipes communicate with the steam-boilers E E in front of the boilers, and are carried around the furnace-walls and connect with pipes H H, which latter pass through the chimney-walls and communicate with the rear end of the boilers E E. Between the longitudinal pipes G G and the boilers E E and the pipes H H are short transverse pipes L L, which are supplied with water from the boilers, and serve

as supports for the pans J J, which are arranged upon them in the usual order, one pan being slightly raised above the other throughout the train, so that the skimmings will all pass toward the defecating-pan or that remotes from the battery-boiler.

K represents the furnace under the battery-pan, and *e* the grate-bars, and *f* the ash-pit.

In the operation of this invention, the fire is built under the steam-boilers in the first place, and when the "steam is up" in the boilers, another fire is built in the furnace K under the battery-pan and the first fire extinguished. The requisite degree of heat is then obtained from the last fire, and the steam kept up in the boilers E E by means of the pipes G G G G, H H, and L L, which are heated in the following manner: The flame from the furnace passes around the battery and partly around the pipes H H, and then passes out between the walls A A and B B, where the train of evaporators, pipes G G G G and L L, and a portion of the steam-boilers' surface are all exposed and receive heat from the flame in its passage to the chimney. The pipes, therefore, keep up the heat in the boilers, and supply the necessary amount of steam, and being exposed to the flame at every point, they economize the surplus heat, which in boilers of the present construction is entirely lost. These water-pipes are all kept below the water-line in the boilers E E, so that if these boilers are kept full there will be no danger of their exploding. The flame after passing under the "coppers" escapes through the flue-space and between the walls A A and C C into the steam-boiler furnace D, where the little heat that is left is given off to the boilers. The flue is then continued to the chimney M. The direction of the currents is indicated by black arrows.

The greatest advantage attained by my system is the economy of heat and of labor, at the same time the works upon my plan can be constructed much cheaper than those in the ordinary manner. I obtain from one furnace all the heat necessary to keep in operation two trains of coppers, besides the steam-boilers, and this accompanied by the particular arrangement above described, and the particular disposition of the pipes communicating with the boilers through the flues.

I do not lay claim to the mode of using the

waste heat from the evaporating or "battery" pan, or pans for evaporating the sugar-juice irrespective of a special arrangement; but

What I do claim, and desire to secure by Letters Patent, is—

The within-described arrangement of horizontal steam-boilers E in rear of furnace K, flue-spaces formed by walls B B, whereby the flame and smoke is directed from the furnace K between the walls or partitions A A and B to the rear of the furnace, and thence under the steam-boilers through the furnace D, where

it finally escapes up through the chimney M, as indicated by the direction of the arrows. This I claim in combination with the pipes G, H, and L, arranged under and serving as supports for the evaporating-pans, all in the manner and for purposes described and represented.

EUGÈNE DUCHAMP.
